ATTORNEY

UNITED STATES PATENT OFFICE.

MICHAEL F. MONIGAN, OF ROSEBANK, NEW YORK.

DOOR SIGN.

Application filed October 22, 1923. Serial No. 670,110.

To all whom it may concern:

Be it known that I, MICHAEL F. MONIGAN, a citizen of the United States, residing at Rosebank, Staten Island, in the county of 5 Richmond and State of New York, have invented new and useful Improvements in Door Signs, of which the following is a specification.

This invention relates to door signs and 10 has particular reference to a door sign for attachment to the inside of a door for informing a person on the outside of the door of certain facts.

The principal object of the invention is 15 the provision of a device for attachment to the inside of a door, and preferably the door of stores, whereby the owner or manager may be located in case of emergency, the device consisting of a sign normally held in 20 a concealed position behind the door and capable of being moved to exposed position by the operation of a push button arranged on the outside of the door.

Another object of the invention is to provide 25 a device of the class mentioned, which includes in addition to the features pointed out above, a sign operable from the inside of a room for displaying certain indicia pertaining to the working hours of the store.

With these and other objects in view, the invention resides in certain novel construction and combination and arrangement of parts, the essential features of which are hereinafter fully described, are particularly 35 pointed out in the appended claims, and are illustrated in the accompanying drawing, in which:—

Figure 1 is an elevational view of my invention applied to a door.

Figure 2 is a vertical sectional view taken 40 on the line 2—2 of Figure 1, but showing the signs in their normal position.

Figure 3 is a vertical sectional view on the line 3—3 of Figure 2.

Figure 4 is a horizontal sectional view 45 on the line 4—4 of Figure 2.

Figure 5 is an elevational view of the changeable sign.

Figure 6 is a vertical sectional view on the 50 line 6—6 of Figure 5.

Figure 7 is a detail horizontal sectional view on the line 7—7 of Figure 5.

Although the device has been mentioned 55 as being applicable to the door of a store, I wish it to be understood that the same may be used for various other purposes, such as

office doors, office desks and the like, as I do not wish to limit myself to the type of door hereinbefore mentioned.

Referring more particularly to the several views in the drawing, the reference numeral 10 designates a door frame of the usual well-known construction, which includes a transparent panel 11, and it is to the inside of the door frame adjacent the 60 transparent panel, that my invention is applied. My invention includes a housing or casing 12, having one of its ends open as at 13, and provided with a partition 14 for dividing the same into compartments 15 and 16. Attaching means in the nature of brackets 17 are employed for securing the housing to the door, but it is to be understood that any suitable means could be employed for this purpose. Mounted in the 70 compartments 15 and 16, are frames 18 and 19 respectively. The frames 18 and 19 are pivotally secured to the housing by means of a pivot pin 20.

The frame 18 supports a suitable sign 21 80 having indicia thereon, such as the name, home address and telephone number of the proprietor of the store upon which the invention is used. This sign is adapted to be exposed in cases of emergency when it is 85 desired to locate the responsible person connected with the store, after closing hours. The frames 18 and 19 are provided on their sides with a lug or shoulder 22, for co-action with a spring pressed pivoted dog 23, the 90 tail of the dog being operable by a spring pressed plunger 24, provided with a manipulating head 25. One of the heads 25 extends to the outside of the door and the other to the inside as clearly shown in Figures 2 and 95 4 of the drawings. In other words the sign 18 is controlled from outside and the sign 19 from the inside.

Normally the signs are concealed in the 100 housing and held therein again movement by the co-acting elements 22 and 23, but when it is desired to expose the same, the plunger 25 is compressed to cause the disengagement of the coacting elements, and a flat spring 26 tends to move the frame about its pivot and through the open end 13 of the housing to a horizontal position as shown in Figure 1 and in dotted lines in Figure 3, wherein the sign may be viewed through the panel 11 of the door.

The construction of the frame 19 is 110 slightly different than the frame 18, and in-

cludes a back section 27 and a front section 28, one slid able over the other. Mounted to the back section 27 of the frame 18, are spaced spools 29, for the winding thereon of 5 a sign strip 30. This strip contains certain indicia such as "We close at 12 m. for lunch" and which indicia is adapted to be brought into registration with the frame opening in the section 28, by means of crank handles 31 which extend beyond one end of the frame. It will be manifest that by forming the frame of two parts, the rolls may be removed when desired, and by reason of the cranks 31 the signs may be changed according to the indicia to be displayed.

From the foregoing description, it is believed that the construction and manner of operation has been clearly set forth and a further explanation is not deemed necessary. However, I do not wish to limit myself to the exact details of construction of my invention herein exhibited, and to nothing less than the whole, limited only by the appended claims.

25 25. What is claimed as new is:

1. In a device of the class described, the combination with a door frame, a housing, attaching means for securing said housing to said door frame, a pivoted sign, coacting means on said sign and housing for holding the sign concealed within the housing, manipulative means for releasing said co-acting means, and a means for automatically moving said sign to an exposed position after 30 operation of said manipulative means.

2. In a device of the class described, the combination with a door frame, a housing, attaching means for securing said housing to said door frame, a pivoted sign having means on said sign and housing for holding the sign concealed within the housing, manipulative means for releasing said co-acting means, and a means for automatically moving said sign to an exposed position after 40 operation of said manipulative means, said

last mentioned means comprising a spring secured to the bottom of the housing.

3. In a device of the class described, the combination with a door frame, a housing, attaching means for securing said housing to said door frame, a pivoted sign, coacting means on said sign and housing for holding the sign concealed within the housing, manipulative means for releasing said co-acting means, and a means for automatically moving said sign to an exposed position after 55 operation of said manipulative means, and means for changing the indicia on said sign without removing the same from its pivotal connection with said housing.

4. In a device of the class described, the combination of a housing open at one side, a supporting structure, attaching means for securing said housing to a supporting structure, a sign pivotally mounted in said housing, a lug formed on said sign, a spring pressed dog carried by said housing for co-action with said lug for locking the sign within said housing, manipulative means extending through said supporting structure 60 and operable for releasing said dog from engagement with said lug, and a spring for moving said sign to exposed position out of the housing upon the actuation of said manipulative means.

5. A door sign comprising a housing, a plurality of compartments formed in said housing, a pivoted member having suitable indicia thereon mounted in each of said compartments, individual means for holding 65 said pivoted members in a vertical position in said compartments, and means for automatically moving said pivoted members to a horizontal position upon operation of the first means so as to expose the indicia on 70 said pivoted member.

In testimony whereof, I have affixed my signature.

MICHAEL F. MONIGAN.
